UNITED STATES PATENT OFFICE.

JAMES P. CLARK, OF OSSIAN, INDIANA, ASSIGNOR TO S. F. BOWSER & COMPANY, INCORPORATED, OF FORT WAYNE, INDIANA, A CORPORATION OF INDIANA.

WAGON-BODY ATTACHMENT.

No. 824,779.

Specification of Letters Patent.

Patented July 3, 1906.

Application filed July 28, 1905. Serial No. 271,675.

To all whom it may concern:

Be it known that I, JAMES P. CLARK, a citizen of the United States, residing at Ossian, in the county of Wells and State of Indiana, have invented a new and useful Wagon-Body Attachment, of which the following is a specification.

My invention relates to attachments for vehicle-bodies, and is especially designed for attachment to vehicles used for delivering or transporting merchandise.

The invention has for its object to provide a rack or cage permanently suspended beneath the rear of a vehicle-body and constituting a carrying device of improved construction in which various objects may be carried—such, for instance, as oil-cans, which it is not desirable to transport in the body of the vehicle along with other merchandise which might become impregnated with the odors of the oil, and thereby injured.

Other objects of the invention are to simplify and improve the construction and operation of this class of carrying devices.

With these and other objects in view the present invention consists in the combination and arrangement of parts, as will be hereinafter fully described, shown in the accompanying drawings, and particularly pointed out in the appended claims, it being understood that changes in the form, proportion, size, and minor details may be made without departing from the spirit of the invention or sacrificing any of its advantages.

In the drawings, Figure 1 is a perspective view of my improved vehicle-body attachment shown in operative position beneath a vehicle-body and with the end-gate opened to form an extension for the rack. Fig. 2 is a view of my improved attachment in side elevation and with the end-gate in a closed position. Fig. 3 is a detail perspective view of the finger for holding the folding partition and the pivoting device. Fig. 4 is a detail transverse sectional view of the finger-pivoting device.

Like characters of reference designate corresponding parts in the several views.

In its preferred embodiment my improved vehicle attachment comprises a plurality of hangers 1, 2, 3, and 4, rigidly secured beneath the rear end of the body 5 of a vehicle. The hangers 2 and 3 are formed integral with sec-

tion 6, and the hangers 1 and 4 are integral with section 7, which, with the longitudinal sections 8, form a substantially rectangular frame disposed in a horizontal plane and parallel with the vehicle-body. Upon the horizontal frame composed of the sections 6 and 7 and 8 is rigidly secured the rack bottom or flooring 9.

About the rack is secured any approved number of retaining-strips 10, secured to the hangers 1, 2, 3, and 4 and forming side rails. Intermediate the ends of flooring 9 is pivotally secured the partition 11 by means of ears 12 and pivot-pins 13. The partition 11 is arranged to fold downwardly upon the flooring 9 of the rack and is held in an upright position by the finger 14 engaging the edge of the partition within the notch 15. The finger 14 is pivoted to a block 16, rigidly secured to one of the strips 10, as by the rivet 17, and is arranged to be held in a horizontal or vertical position by means of the angular edge 18 engaging within the notches 19 and 20 and retained by the spring 21, exerting tension on pivot-pin 22.

Adjacent the lower ends of hangers 2 and 3 blocks 23 are secured to the frame-pieces 6, and between the said blocks 23 and the hangers are pivoted the extremities of end pieces 24.

The end pieces 24 are formed integral with the cross-piece 25, forming the frame for the end-gate of the rack or cage, which is completed by the retaining-strips 26. Upon the pivots 27, upon which the end pieces 24 are pivoted are pivotally secured radial bars 28, formed integral with segments 29, secured by a folded portion 30 to the end pieces 24. Intermediate their ends the radial bars 28 are provided with outstanding curves 31, arranged to clear the strips 10. The segments 29 are held adjacent the hangers 2 and 3 and guided by the clips 32, secured to the hangers, as by the rivets 33 passing through the clips and the hangers and also through the strips 10, which extend outwardly beyond the clips and are provided with the notches 34. The movement of the segments and the closure about the pivot 27 is limited by the lugs 35, turned upon the segments and engaging with the hangers 2 and 3 when the closure is in a plane with the rack-bottom 7.

Upon the pins 27 are also pivoted lever

- members 36, carrying the bearing-lugs 37, slidably in which are mounted levers 38. The levers 38 are provided with keepers 39, embracing the segments 29 and arranged to engage notches 40 in the segments and held in engagement by the springs 41 bearing against the lever member 36 and against collar 42, adjustably secured to the lever 38, as by the set-screws 43. The pivoted members 36 and the spring-actuated levers 38 coöperate to constitute latch members. The extremities 44 of the levers 38 are connected by a transversely-disposed bar 45, which when the gate is open constitutes an end rail.
- 15 The operation of my improved vehicle-body attachment is as follows: Normally the parts will be in the position shown in Fig. 2, and when it is necessary to load the rack the bar 45 and the levers 38 are pushed toward the pivot 27, thus disengaging the keepers 39 from the notches 34, by which it and the gate are held in the closed position. With the catch thus released the gate may be opened and with the bar in dotted position shown in Fig. 1 offering no obstruction to the introduction of articles upon the flooring 7. If the nature and quantity of goods make it desirable, the partition 11 may be raised and held in upright position by the finger 14.
- 20 30 The goods being loaded, the gate is again closed, as in Fig. 2, to retain the articles within the rack. If more goods are to be transported than can be loaded within the rack and upon the flooring 7, the gate may be left in the position shown in Fig. 1 and the rail 45 raised to the full-line position, engaging notches 40 of segments 29 and serving as a means for retaining the goods upon the gate and within the rack proper.
- 25 35 40 With the parts in the position shown in Fig. 1 if it is desired to close the gate the bar 45 may be grasped and swung upwardly on the pivot 27. When the keeper 39 contacts with the bevel end of the catch 34, the keeper will be thereby automatically disengaged from the notch 40, permitting the segments 29 and gate to complete the movement until the notch 40^a engages the keepers 39 to hold the gate in a closed position.
- 45 50 Having thus described the invention, what is claimed is—
1. A carrying rack or cage, supporting-hangers for the same, an end-gate hingedly supported adjacent to the bottom of the cage, segment-strips connected with the end-gate and having stop-lugs, latch members pivoted adjacent to the ends of the gate and having keepers embracing the segment-strips and an end rail connecting the latch members.
  - 55 60 65 2. An end-gate having segmental guide-strips, latch members pivoted adjacent to the ends of the gate and having keepers embracing the segment-strips and adapted to engage notches in the latter, and an end rail connecting the latch members.
3. A carrying-cage, a hinged end-gate for the same, means for supporting the end-gate in an approximately horizontal position, and an adjustably-supported end rail.
4. A carrying-cage, an end-gate for the same, segmental guide-strips connected with the end-gate, pivoted members having keepers adjustably engaging the guide-strips, and an end rail connecting the pivoted members.
5. A carrying-cage, supporting-hangers for the same, a hingedly-supported end-gate having segmental guide-strips, pivoted latch members having keepers embracing the guide-strips and adapted to engage notches therein, and side walls having terminal beveled ends and notches to engage the keepers.
6. A carrying-cage, an end-gate for the same, guide-strips connected with the end-gate, pivoted members adjustably engaging the guide-strips, and an end rail supported by said pivoted members.
7. A carrying-cage, supporting-hangers for the same, an end-gate for said cage adapted to form an extension of the bottom thereof, means for supporting said extension, and an adjustable end rail.
8. A carrying-cage, supporting-hangers for the same, an end-gate for the cage adapted to form an extension of the bottom thereof, means for supporting said extension, pivoted members adjustably connected with the supporting means, and an end rail connected with said pivoted members.
9. In a device of the class described, a rack, a partition pivotally secured in the rack, and means for holding the partition in operative position.
10. In a device of the class described, a rack, a partition pivotally mounted and arranged to fold into the bottom of the rack and means for holding the partition upright.
11. In a device of the class described, a rack, a partition horizontally pivoted to and arranged to fold into the bottom of the rack, and means for holding the partition upright.
12. In a device of the class described, a rack, a partition horizontally pivoted to and arranged to fold into the bottom of the rack, and a finger pivoted to the rack and arranged to engage and hold the partition in an upright position.
13. In a device of the class described, a rack, a gate for the rack, a partition pivoted to and arranged to fold into the bottom of the rack, means for holding the partition in an upright position, and means whereby when the gate is open it forms an extension to the bottom of the rack.
14. In a device of the class described, a rack, a gate for the rack, a partition pivoted longitudinally of the rack and arranged to fold into the bottom, a finger pivoted to the rack and arranged to engage and hold the partition in an upright position, and a gate horizontally and transversely pivoted to the

rack and arranged to form when open an extension of the rack-bottom.

15. A device of the class described comprising a vehicle-body, hangers secured beneath the rear end of the body, a rack-bottom rigidly carried by the hangers, segments centrally pivoted to opposite hangers, a gate rigidly carried upon the segments, levers pivoted at the centers of the segments and a bar connecting the extremities of the levers.

16. A device of the class described comprising a vehicle-body, hangers secured beneath the rear end of the body, a rack-bottom rigidly carried by the hangers, segments centrally pivoted to opposite rear hangers, a gate rigidly secured to the radii of the segments, means for holding the gate in a plane with the rack-bottom, levers pivoted at the

centers of the segments and provided with clips engaging the arcs, springs arranged to hold the clips in engagement with notches formed in the arcs, a bar connecting the extremities of the levers, means for holding the gate and bar in a closed position, a partition horizontally and longitudinally pivoted within the rack and arranged to fold into the bottom, and a finger pivoted to the side of the rack and arranged to hold the partition in an upright position.

In testimony that I claim the foregoing as my own I have hereto affixed my signature in the presence of two witnesses.

JAMES P. CLARK.
